Primary Examiner — Richard E Chilcot*(74) Attorney, Agent, or Firm* — Ladas & Parry LLP(57) **CLAIM**

The ornamental design for a machine gun, as shown and described.

DESCRIPTION

The file of this patent contains at least one drawing/photograph executed in color. Copies of this patent with color drawing(s)/photograph(s) will be provided by the Office upon request and payment of the necessary fee.

1. Machine gun
- 1.1 : Perspective
- 1.2 : Right
- 1.3 : Left
- 1.4 : Front
- 1.5 : Top
- 1.6 : Back
- 1.7 : Bottom

1 Claim, 7 Drawing Sheets
(7 of 7 Drawing Sheet(s) Filed in Color)
